UNITED STATES PATENT OFFICE.

STERLING ELLIOTT, OF NEWTON, MASSACHUSETTS.

ADDRESSING-MACHINE.

1,220,734.

Specification of Letters Patent. Patented Mar. 27, 1917.

Application filed October 11, 1913. Serial No. 794,620.

To all whom it may concern:

Be it known that I, STERLING ELLIOTT, a citizen of the United States, residing at Newton, in the county of Middlesex and State of Massachusetts, have invented an Improvement in Addressing-Machines, of which the following is a specification.

This invention relates to addressing machines, and has for its object to construct a simple machine adapted to be operated by one hand while the other hand is employed for delivering envelopes which are to be printed to the machine, and for taking away the printed envelopes.

15 The machine embodies many of the characteristic features of the large and more expensive machines, and, although not having the capacity of such machines, yet the quality of work done is the same and the capacity is such as to meet the demands of many small users.

20 The machine here shown for illustrating my invention embodies a pair of horizontal guide-bars arranged to form a stencil-passage which extends from a stencil-supply compartment at one end of the machine to a stencil receiving compartment at the other end of the machine; an envelop-passage arranged beneath said stencil-passage adapted to admit of envelopes being placed by hand in proper position for printing, and subsequently removed; said passage preferably having a gage, a printing-device for coöperation with the stencils to print the envelopes, said printing-device comprising a pair of rotatable co-acting sectors for successively engaging the stencils and envelopes and while performing the function of printing the envelopes, act to move the stencils

25 and envelopes along the stencil-passage and envelop-passage, and upon disengaging them permit the printed envelopes to be removed and the stencil to be pushed along by the next succeeding stencil and thrust through the entrance and into the stencil receiving compartment at the bottom; a hand-actuator to which said printing-device is connected; a reciprocating feeding-device connected with said hand-actuator for feeding the stencils along the stencil-passage

30 into position to be engaged by the printing-device; a friction-device for engaging the stencils in front of the printing-device to check or retard their progress at such point, as the movement of the feeding-device, when performed by hand, is liable to be more

or less irregular; an inking-mechanism for the printing-sector comprising a rotatable roll for delivering ink to said sector adapted to be repeatedly engaged and rotated by said sector, and having hand-engaging means for rotating it independently of said sector, when desired, a rotatable and axially movable roll for transferring ink to said ink-delivering roll, which is yieldingly held in engagement with said roll, having hand-engaging means for rotating and moving it axially, and an ink-supplying cylinder arranged for engagement with said rotating and axially movable roll, the weight of which cylinder is supported by said roll, said ink-supplying cylinder having hand-engaging means for operating it to force the ink through perforations therein.

35 In some respects the present invention is an improvement upon the machine of Letters Patent #592,603, dated October 26, 1897; and the ink-supplying cylinder is or may be constructed substantially as represented in Letters Patent #1,036,200 and #1,036,201, dated August 20, 1912.

40 Figure 1 is a rear side elevation of an addressing machine embodying this invention.

45 Fig. 2 is a front side elevation of the machine shown in Fig. 1.

50 Fig. 3 is a plan view of the machine shown in Fig. 1.

55 Fig. 4 is a transverse vertical section of the machine shown in Fig. 1, taken on the dotted line 4-4.

60 Fig. 5 is a longitudinal vertical section of one of the rolls of the inking-mechanism.

65 Fig. 6 is a detail view of the printing-device.

70 Fig. 7 is a detail view of the friction-device which engages the stencils in the stencil-passage.

75 Fig. 8 is a detail view of the lifting-means for the stencils at the bottom of the stencil-receiving compartment, whereby the pile of stencils is lifted by a stencil which is being thrust into the compartment at the bottom.

80 Fig. 9 is a detail view of a gage which is arranged in the envelop-passage.

85 10 represents the base of the machine, upon which a pair of long guide-bars 12, 12, are arranged in parallel relation, said bars having grooves in their adjacent faces, thereby to form a horizontal guideway or 90 passage for the stencils. Said guide-bars extend from a stencil-supply compartment

at one end of the machine to a stencil-receiving compartment at the other end of the machine, and each compartment is adapted to contain a pile of stencils. The supply-compartment is or may be formed by a pair of cross-bars 14, 14, attached at their ends to the guide-bars and having uprights 15, 15, rising from them, formed with right angularly formed sides, which uprights serve as 5 end and side walls for the compartment. The stencil-receiving compartment is similarly formed, it comprising a pair of cross-bars 16, 16, attached at their ends to the guide-bars and having uprights 17, 17, rising from them provided with right angularly formed 10 sides, which serve as end and side walls for the compartment. The inner faces of the sides of all said uprights are arranged in line with the bottoms of the grooves in the 15 guide-bars. The upper lips of the grooves of the guide-bars are cut away along those portions thereof between the uprights of each compartment, so that the stencils may be introduced at and removed from the top 20 of the compartments, respectively, and while contained therein will rest upon or be supported by the lower lips of said grooves. The stencils are taken, *seriatim*, from the bottom of the pile contained in the supply- 25 compartment and are moved along the stencil-passage far enough to be engaged by the printing-device, by means of a reciprocating sliding pusher 20, made as a plate, which enters and slides along in the grooves in the 30 guide bars 12, 12, and said pusher has loosely connected with it one end of a link 21, the other end of which link is connected to a hand-actuator, here shown as a double-crank arm 22, secured to a shaft 23, and having a 35 handle 24 for rotating it. During each rotation of the crank-arm the pusher is moved forward and returned to normal position, thus feeding the stencils forward along the stencil-passage and returning to engage the 40 next stencil. The stencils are thus fed forward a distance equal to the length of a stencil or thereabout, which it will be understood is far enough for them to occupy a position to be engaged by the printing device. 45

The guide-bars 12, 12, are attached at one end only, to a raised portion on top of the base 10, and their unattached portions extend over the remainder of the top of the 50 base and also beyond the end of the base for a suitable distance, as shown in Fig. 1, said unattached portions occupying an elevated position above the top of the base, thereby to provide a narrow space or passage beneath them and above the top of the base 55 for the envelops, said envelop-passage being represented at 25. This envelop-passage is, therefore, open at the end and both sides and enables the envelops to be inserted by hand 60 below the stencil-passage, so as to be en-

gaged by the printing-device, and to be subsequently removed.

The envelop-passage is or may be supplied with a gage, here shown as a bar 26, see Figs. 4 and 9, of a thickness corresponding to the height of the passage and arranged longitudinally with respect thereto, against which the edge of an envelop may be brought to bear when inserted in the passage; a short bent arm 27 supporting said bar, and a bar 28 to which said arm 27 is attached, which bar 28 is extended transversely across the top of the guide-bars and is slidably supported and held in any adjusted position thereon by a clamp 29 arranged on one of the guide bars. A thin plate 30 is also attached to the gage-bar 26, at the top, which extends over the under side of the guide-bars 12, 12, to close that portion of the stencil-passage between the guide-bars and envelop-passage for a short distance in front of the printing-device, and thereby prevent the edges or end-portions of the envelops from being thrust upward against the stencils or through the stencil-passage between 70 the guide-bars. 75

The printing-device is arranged intermediate the length of the guide-bars, and is designed to engage both the stencils and envelops, and to feed them both forward while printing the envelops, and then to disengage them, permitting the printed envelop to be removed, the stencil at such time reposing in the stencil-passage, preparatory to being moved along and thrust into the stencil-receiving compartment at the bottom, by the next succeeding stencil which is fed forward by the printing-device. Said printing-device comprises essentially two plane faced sectors 35, 40, similar to that shown in Letters Patent #592,603. The sector 35 is arranged above the stencil-passage and is secured to the hand-operated shaft 23, so that it may be rotated by hand at the same time the feeding-device is operated. The sector 40 is arranged below the envelop-passage and is secured to a shaft 41, having its bearings in one end-portion 42, of the lever, pivoted at 43, the other end-portion 44 of said lever having a hole 100 through it to loosely receive a stud 45, which is encircled by a spring 46, so that said end-portion 44 bears against the spring and the spring acts to yieldingly resist movement of the lever and sector borne by it, thereby admitting envelops of varying thicknesses to be introduced into the envelop-passage which will be engaged with substantially an equal pressure by the sector. A toothed gear-wheel 47 is secured to the shaft 41, which is engaged by a toothed gear-wheel 48, secured to the shaft 23, so that upon turning said shaft 23 by hand, both sectors will be rotated simultaneously, and when in the position shown in Fig. 1, they will ad- 105 110 115 120 125 130

mit of the stencils being fed forward at least to the point of tangency of the sectors and of the envelops being introduced, and when in the position shown in Fig. 6 5 they will engage both the stencil and envelop and as rotation continues both the stencil and envelop will be fed forward while the printing is being done. When the sectors have been turned far enough to dis- 10 engage a stencil and envelop the printed envelop may be removed, the stencil will have been moved along the stencil-passage a distance substantially equal to its length or thereabout, and so as to be subsequently 15 pushed forward, by the next succeeding stencil, entirely through the entrance at the bottom of the stencil-receiving compartment.

Within the stencil-receiving compartment and adjacent the entrance thereto a pair 20 of bosses 55, 55, having inclined tops, here shown as curved, are arranged on the bottom lips of the grooves of the guide-bars, see Fig. 8, thus occupying positions in the path of movement of the stencils, and the 25 stencils which enter said compartment are moved over these bosses, and during such movement are caused to tip first upward and then downward and finally to rest in a downwardly inclined position with their rear 30 ends projecting over the tops of the bosses, said rear ends being thereby held in an elevated position, so that the front end of the next succeeding stencil will, when thrust into the compartment, first engage the uplifted 35 rear end of a downwardly inclined stencil and then will be slid along beneath said stencil and moved into a downwardly inclined position, and thus become the bottom stencil of the pile.

40 When hand actuated means is employed for feeding stencils forward into position to be engaged by the printing-device it will be understood that their movement is liable to be more or less irregular, and to prevent 45 the stencil from bounding forward in the stencil-passage, a friction-device is arranged therein, just in front of the printing-device, which, as shown in Fig. 7, consists of a lip 50, formed on a clip 51, and arranged on 50 one of the guide-bars 12, said lip 50 being extended downward into the stencil-passage far enough to engage one of the edge portions of the stencils. Such a friction-device is also of advantage in retarding or check- 55 ing forward movement of the stencils in other forms of addressing-machines.

The inking-mechanism for the printing-device, as here shown, comprises an ink-delivering roll 60, an ink-transferring roll 65, and an ink-supply roll 70. The ink-delivering roll 60 has a plane face for engagement with the printing-sector 35, and is loosely journaled in the frame, and is adapted to be rotated by the printing-sector 60 65 when the latter is in frictional engagement

with it, and is also adapted to be rotated by hand, when desired, it having a handle 61 provided for this purpose.

The ink-transferring roll 65 has a plane face for engagement with the ink-delivering 70 roll 60 and ink-supply roll 70, and is journaled in an arm 66, which is pivotally supported on the shaft 23, or other convenient support, and which is yieldingly held in elevated position with the roll borne by it in 75 engagement with the rolls 60 and 70, by means of a spring 67, which is attached at one end to the arm and at the other end to a fixed point. Said roll 65 is rotatable and also movable axially, and, as here shown, it 80 has secured to one of its journals a knob 68, see Fig. 5, adapted to be engaged by hand for the purpose of thus moving it, and its bearings in the arm admit of a sliding as well as a rotating movement. The ink-sup- 85 ply roll 70 is or may be made substantially as shown in Letters Patent #1,036,200 and #1,036,201, aforesaid, and is adapted to supply ink through numerous perforations in its plane cylindrical face by turning the 90 knob 71, while holding the knob 72 stationarily. Thus, to supply ink said roll 70 is rotated and the ink caused to project through the numerous perforations in its cylindrical wall, and the roll 65 is then ro- 95 tated and moved axially by hand, and then the roll 60 is rotated by hand until the plane face of said roll 60 becomes covered with ink, which, it will be understood is sufficient to last for a short period of time, and then 100 these operations are repeated. The ink-supply roll 70 is held in elevated position by the roll 65, so that the weight of said roll 70, is borne by said roll 65, and, as said roll 65 is held in frictional engagement with the 105 roll 60 it will be seen that all of the rolls will be rotated by the printing-sector 35. This form of inking-mechanism is simple and adapted to be operated by hand and well subserves its purpose, although it will be 110 understood that, so far as other features of the invention are concerned, other forms of inking-mechanism may be employed.

I claim:

1. An addressing machine comprising a 115 base having a flat top with a raised portion thereon at one end, a pair of grooved guide-bars arranged horizontally on said raised portion, and extended over the remainder of the top of the base in an elevated position, 120 to provide a space beneath them for an envelop, a pair of uprights arranged on said bars at one end to form a supply-compartment for the stencils, and a pair of uprights arranged on said bars at the other end to 125 form a receiving-compartment for the stencils, those portions of the upper lips of the grooves of said bars between the uprights of each compartment being cut away, substantially as described. 130

2. An addressing machine comprising a base having a flat top with a raised portion thereon at one end, a pair of grooved guide-bars arranged horizontally on said raised portion, and extended over the remainder of the top of the base in an elevated position to provide a space beneath them for an envelop, a pair of uprights arranged on said bars at one end to form a supply-compartment for the stencils, and a pair of uprights arranged on said bars at the other end to form a receiving-compartment for the stencils, those portions of the upper lips of the grooves of said bars between the uprights of each compartment being cut away, means arranged at the bottom of the receiving-compartment to cause the stencils, when thrust thereinto to tilt and thereafter to hold them with their rear ends in elevated position, and means arranged to feed the stencils intermittently from one to the other compartment, substantially as described.
3. An addressing machine comprising a pair of horizontal bars having guiding-grooves arranged facing each other, uprights arranged on said bars to form a stencil-receiving compartment, the upper lips of the grooves of said bars between said uprights, being cut away and bosses, with inclined tops, arranged on the lower lips of said bars in the path of movement of the stencils, and adjacent the entrance to the compartment, said bosses acting to cause the stencils, which enter the compartment, to move first in an upwardly inclined direction, and then in a downwardly inclined direction, and to finally hold them with their rear ends in an elevated position, substantially as described.
4. An addressing machine comprising a pair of horizontal bars having guiding-grooves arranged facing each other, a pair of cross-bars secured to said guide-bars, each cross-bar having uprights with angularly formed sides, the inner faces of the sides being arranged in line with the sides of the grooves, the upper lips of the grooves of the guide-bars being cut away between said cross-bars, thus forming a receiving-compartment for the stencils, and bosses having inclined tops arranged on the lower lips of the grooves near the entrance to the compartment, in the path of movement of the stencils, which cause the stencils, which enter the compartment, to tilt, and to subsequently hold them with their rear ends in elevated position, substantially as described.
5. An addressing machine, comprising a pair of rotatable sectors arranged, respectively, above and below a stencil-passage and an envelop-passage for engaging, at their points of tangency, a stencil and an envelop contained in said passages, gearing connecting said sectors and a double crank-arm with handle connected with one of the sectors for rotating them, a supply-compartment for stencils associated with the stencil-passage, a sliding-pusher arranged for reciprocation in the stencil-passage and a link pivotally connected at one end with said pusher and loosely mounted at its other end on said double crank-arm, substantially as described.
6. An addressing machine comprising a pair of horizontal guide-bars arranged to form a stencil-passage and in connection with their support to form an envelop-passage beneath them, a stencil-receiving compartment located at the end of said stencil-passage, and opening thereto at its bottom, a pair of sectors arranged respectively in planes above and below the stencil-passage and envelop-passage to engage the stencils and envelops and feed them along the passage into the receiving-compartment, means to supply one of said sectors with ink, and means to feed the stencils along the stencil-passage into position to be engaged by the sectors, substantially as described.
7. An addressing machine comprising a pair of horizontal guide-bars arranged to form a stencil-passage, said bars being supported at one end and disposed a short distance above the base to provide a horizontal passage beneath them which is open at the side and at one end to receive and permit forward movement of an envelop, a receiving-compartment for the stencils arranged at one of the ends of said guide-bars, and having an entrance at its bottom, leading into the end of the stencil-passage, a pair of sectors arranged respectively in planes above and below the stencil-passage and envelop-passage to engage the stencils and envelops and feed them along their respective passages and into the receiving-compartment, means to supply one of said sectors with ink, and means to feed the stencils along the stencil-passage into position to be engaged by the sectors, substantially as described.
- In testimony whereof, I have signed my name to this specification, in the presence of two subscribing witnesses.
